CHARLES GILBERT HAWLEY, OF CHICAGO, ILLINOIS, ASSIGNOR TO CENTRIFIX CORPORATION, OF CLEVELAND, OHIO, A CORPORATION OF OHIO

BOILER-OUTPUT CONTROL

Application filed March 5, 1926. Serial No. 92,476.

My invention relates to a method of and means for controlling the steam output of boilers to the end that the steam shall leave the same in a dry and clean state or reversely 5 to the end that the boiler water shall be retained in the boiler and prevented from escaping at the steam outlet along with the steam.

In the operation of steam boilers, and, 10 particularly, in the case of steam locomotives serious difficulties are experienced because of the surging of the boiler water. Added to by the violent and unequal liberation of steam at the different points, the 15 surging so disrupts the steam disengagement surface as to throw masses or slugs of water into the steam space, with the result that much of it is carried away through the outlet or nozzle by the escaping steam. Thus, 20 the steam leaving the boiler becomes a vehicle for moisture and solids and in many instances large quantities thereof pass into the engines, turbines, and other steam units, which should receive only dry and clean 25 steam from the boiler. Any steam super-heater that may be interposed is likewise fouled and rendered inefficient.

The objects of my invention are to overcome these difficulties and to avoid the main- 30 tenance and equipment costs involved thereby.

As will become apparent, my invention in several of its embodiments, is of general applicability and will be found to be of ad- 35 vantage in all steam boilers and evaporators, whether working under pressure or vacuum. But in the drawings, that form part of this specification, the invention is illustrated in 40 that form which seems best adapted to locomotive boilers, where the difficulties to be surmounted are the greatest.

In the drawings, Fig. 1 is a transverse vertical section of a typical steam locomotive boiler equipped with the structures that embody the present invention.

Fig. 2 is a vertical longitudinal section of the same boiler and structures except that the throttle valve is replaced by an open standpipe.

Fig. 3 is a horizontal section on the line $x-x$ of Figs. 1 and 2.

It will be seen that only the upper middle portion of the locomotive boiler is shown in the drawings. The wrapper sheet is marked 55 2. The upper forward corner of the fire box is marked 3, and the flues 4. The shell or barrel of the boiler is marked 5 and the dome 6, and the dome cap, 6'. The steam outlet or so-called drypipe is marked 7 and, 60 as usual, leads to the front end of the boiler. At the rear end of the drypipe is a stand- pipe 8, which extends into the top of the dome. As shown in Fig. 1, the standpipe may be equipped with a throttle valve 9, or it may 65 have a simple open upper end, as shown at 10 in Fig. 2, the latter being characteristic of a construction in which the throttle valve is arranged at the forward end of the dry- pipe, usually in the smoke box.

The part of the shell or barrel which is covered by the dome 6, contains a large opening 11, through which the standpipe 8 rises; and through which access may be had to the interior of the boiler when the dome cap 6' 75 is removed. The normal water level is indicated by the line WL. The surface thus indicated will also be referred to as the steam disengagement surface.

In modern locomotives, the boilers are of 80 such great size as to leave little clearance space at the top and the steam domes must of necessity be so low as to almost disappear so far as being a distinguishing boiler element is concerned. Perforce, the said dis- 85 engagement surface dangerously approaches the level at which the steam escapes into the top of the stand-pipe or outlet. Unless preventive means be devised it is inevitable that water shall be elevated from the disengage- 90 ment surface and discharged through the outlet with the steam. As dry pipe steam outlet velocities ranging from 6,000 to 12,- 000 feet per minute are common, it should be 95 apparent that although moderately dry steam is secured from high domed, small locomotive boilers, in the case of the larger locomotives the supply of dry steam is defeated for, in fact, every tendency seems to be directed toward emptying the boiler of wa- 100

ter, as well as of steam. These tendencies are aggravated whenever the disengagement surface is fouled with impurities and worse when actual foaming conditions are encountered. They are augmented when the boiler is fired at high ratings, at which times the disengagement surface is violently agitated by the numberless ascending steam bubbles from the evaporating surfaces of the boiler. And, further, the forces tending to elevate the water and discharge it at the steam outlet are made more certain of action by the surging and splashing of the boiler water as the locomotive lurches and rolls upon the rails and at times when the brakes are applied and with every sudden curve and change of grade. Such motions of the boiler throw quantities of water into the steam space and result in "slugging" the dry-pipe, the superheater, the valves and the engines, and even the auxiliary steam users such as the air compressor and the head light turbine are affected.

The major difficulties encountered have been described at greater length than usual in order that the simple constructions involved in this invention may be better appreciated and more clearly understood.

The primary element of the present invention is the part of structure to which I have given the name "pool". It is in fact a relatively quiet pool of boiler water, set aside or separated from the major disengagement surface. This pool is defined by an encompassing wall that rises from a point below the safe low water level in the boiler and extends nearly to the top of the boiler shell. This pool is located around and beneath the steam outlet; in this case directly beneath the steam dome. As will become clear, the dip of the wall into the boiler seals off the lower end of the pool as a steam entrance, except for such steam as may be disengaged at the surface of the pool itself. Thus the steam must find another path over which to reach the steam dome and outlet. To reach the latter, the steam from the major disengagement surface must pass over or through the top of the pool defining wall. As will be explained in detail, any particles and masses of water that may be carried by the steam are thrown down into the pool of water within the confines of the encompassing wall. The steam having been freed of its burden of moisture rises freely above the pool and passes into the dome, thence to enter the steam outlet or drypipe. The main volume of steam enters in this manner. A minor volume of steam, important in its effects, rises directly within the pool being disengaged from the surface thereof.

As another and very desirable element of the invention I prefer also to interpose between the top of the steam pool and the steam outlet a mechanical steam wringer or puri-

fier, by which even the most minute particles of moisture are also withheld from the steam outlet; all to the better advantage of the superheater, the steam lines, valves and engines.

From the foregoing it should be evident that while my invention perhaps meets the greatest need in the case of locomotive boilers, it is also generally applicable to all boilers and evaporating vessels, being well adapted for use wherever vapor is released from a disengagement surface of sufficient extent to admit of its described subdivision and is so close to or in such restricted communication with the steam outlet as to require so definite measures to prevent the carrying over of entrained moisture.

In the drawings, the above described steam pool is marked P and will be seen to be defined by the encompassing wall W. This wall may be of any desired shape in horizontal cross section but is preferably cylindrical, as well shown in Fig. 3. As there shown it is composed of five vertically separated curved sections; two of these 12-12 meet above and below the drypipe 7. The pair of sections 13-13 are at the sides and the section 14 is at the rear side or end, opposite the standpipe 8. The edges of the sections are flanged as well shown at point 15, and are joined by a plurality of easily removable bolts 16. As access to the boiler here shown is gained through the dome, all of the fastenings 15-16 are placed upon the inner side of the part or wall W; and it will be understood that the part W is of such generous size as to easily accommodate a man.

The open lower end 17 of the wall W (and pool P) is somewhat above the flues 4, to avoid wear on the latter. The upper end of the wall W is curved to correspond to the inner side of the boiler shell and is separated therefrom by an annular opening 18, which latter constitutes the main steam entrance. A sectional splash flange 19 is preferably used upon the exterior of the wall W just below the steam entrance opening 18.

The depending flange, collar or sleeve 20 has two important functions. It is spaced inwardly from the wall W and forms a baffle which prevents the direct passage of the steam from the annular opening 18 into the dome. Second, the sleeve or collar 20, as here shown, also serves as a support from which the wall, W, hangs, as through the medium of the hanger bars 21. The upper ends of the hangers 21 may be riveted or otherwise permanently fastened to the depending collar. Their lower ends are attached to the side wall sections 13 by keys or bolts 22. As a rule only the wall section 14 need be removed to permit entrance to the interior of the boiler but at times all of the sections should be taken up. Hence, the employment

of the detachable hanger fastenings 22. Obviously, the upper end of the collar 20 is conveniently fastened to the walls of the dome opening 11. Where this is not feasible the collar should be hung close against the under side 5' of the boiler shell; for in every case the collar 20 must prevent the direct passage of steam from the body of the boiler into the dome.

The short lug or part 23 is attached to the collar 20 and serves to brace the upper end of the wall section 14 against the thrust of the surging water. The other sections brace against the collar through the medium of their internal flanges 15.

Special attention is called to the fact that the steam pool occupies only a very minor part of the disengagement surface. Further, the pool defining wall or structure is of such moderate width that it occupies only a minor part of the transverse section of the boiler. Thus, the spaces S', S' on opposite sides of the pool are left amply large to permit an inspector or workman to move along the tops of the flues from end to end of the boiler.

Generally, the surface WL is in a very disturbed state, due to the ebullition of the water. And the water splashes heavily from side to side and end to end when the locomotive is in motion. In consequence, the steam space S is filled with steam that usually is heavily overburdened with particles and masses of water. The burdened steam enters the annular opening 18 at the top of the pool and encountering the annular baffle or collar 20 is deflected downward. Thus, the heavier water is caused to plunge into the relatively quiet water of the pool, leaving the steam free to rise into the dome with little if any burden of moisture.

Here follows the action of the steam refining or purifying devices which my invention prescribes for use within the dome itself, and which functions to throw down any moisture which may perchance rise from the steam pool. As shown, the dome is divided into upper and lower parts by a floor or horizontal partition 24 at about the level of the top of the standpipe 8. The devices 25 are located at respective holes 24' in the floor 24 and are so called full automatic centrifix units, meaning that the units are of such form that the collected water is thrown back into the boiler and need not be discharged to a point outside of the boiler. They provide avenues through which the steam must pass in order to enter the space 26 in the extreme top of the dome 6. The floor accommodates the upper end of the standpipe or pipes and they, therefore, receive steam only from the dry steam space 26. Each unit is composed of a top 25' having an opening that registers with the opening 24' in the floor 24, and a bottom 25'', and a generally cylindrical side wall 25''. The latter comprises a plurality

of tangential blades between which are tangential openings or tuyères leading inward. The steam from the lower part of the dome perforce enters tangentially and takes on a whirling motion within the unit 25. The effect of this whirling motion within the defined unit structure is to throw down the entrained moisture. The moisture drains back into the pool from the bottoms of the units 25 while the clean dried steam passes upward through the holes 24', thus entering the dry space 26 and gaining access to the throttle valve or open upper end of the standpipe.

In some cases it is desirable to avoid collections of water in the lower corners 6'' of the dome; hence, the drain holes 6^a in the overlapping edges of the boiler shell. The water drains away freely, but only because of the fact that the opening 18 at the top of the steam pool is amply large. That is, the supply of steam to the interior of the pool P is sufficient to maintain the same pressure within the pool and dome as within the main steam space S of the boiler.

Attention is called to the fact that the steam entrance opening 18 at the top of the steam pool may be so restricted as even to wire-draw the steam over the top of the wall W. It is a question whether the downwardly deflecting action of the baffle collar 20 is or is not improved by restricting the capacity of the annular opening 18. As stated, the aggregate opening may be so restricted as to make its area little greater than the area of the throttle valve and drypipe. This notwithstanding the fact that an apparent drop of pressure within the pool would cause the elevation of the surface of the water therein. Such elevation will not take place. Indeed, it is a feature of my invention to prevent a drop of pressure within the pool. This prevention is accomplished very simply, to wit:—by the accelerated evaporation of steam from the surface of the pool,—a natural and inevitable result of any tendency toward a lower pressure within the pool. To the end that this feature of my invention shall be clearly understood, attention is again directed to the fact that the boiler is assumed to be in operation under steam and that the surface of the pool is no more than a part of the whole disengagement surface WL.

From all practical standpoints I recommend that the area of the intake opening 18 be made several times that of the drypipe in order that the velocity of the steam at that point shall be relatively lessened. By doing so there is assurance that the greater burden of water will be thrown down before the steam reaches the opening 18, lessening by that much the work to be done by the pool.

Various modifications and adaptations of my invention will readily suggest themselves to those who are skilled in the art of separating entrained moisture from vapors and,

therefore, I desire that it be definitely understood that my invention is not limited to the precise structures herein shown and described.

Having thus described my invention, I claim as new and desire to secure by Letters Patent:

1. The described method of "drying" steam and like vapors previous to emission from the vapor outlets of an evaporating vessel, that consists in organizing an open bottomed liquid and vapor pool around and below the outlet of an area several times larger than said outlet, but nevertheless in its lower part embracing a minor part of the disengagement surface in the vessel, conducting the vapor from the major part of said disengagement surface through the upper part of said pool and thus to said outlet, and simultaneously throwing the entrained liquid downward in said pool while permitting the vapor to escape at said outlet.

2. The described method of "drying" steam and like vapors previous to emission from the vapor outlets of an evaporating vessel, that consists in organizing an open bottomed liquid and vapor pool around and below the outlet of an area several times larger than said outlet, but nevertheless in its lower part embracing a minor part of the disengagement surface in the vessel, conducting the vapor from the major part of the disengagement surface into the upper part of said pool and thus toward said outlet, simultaneously throwing the entrained liquid downward in said pool, permitting the vapor to rise in said pool, and finally wringing the remaining moisture from the vapor before permitting it to escape at said outlet.

3. The described method of "drying" steam and like vapors previous to emission from the vapor outlets of an evaporating vessel, that consists in organizing an open bottomed liquid and vapor pool below the outlet of an area several times larger than said outlet, but nevertheless in its lower part embracing a minor part of the disengagement surface in the vessel, conducting the vapor from the major part of said disengagement surface to said outlet through the upper part of said pool, simultaneously wringing the entrained moisture from the vapor and throwing it downward upon said minor part of the disengagement surface while permitting the vapor to rise and escape at said outlet, and meantime supplying any deficiency of pressure within said pool by evaporation from said minor part of the disengagement surface.

4. A steam "drying" pool structure beneath the vapor outlet partially submerged in the boiler water and embracing a minor part of the vapor disengagement surface in the boiler, in combination with a baffle at the top of said pool and adapted to cause entrained moisture to plunge into said part of the dis-

engagement surface, and auxiliary vapor drying means interposed between said baffle and said outlet.

5. A boiler and its vapor outlet, in combination with a baffle attached to the under side of the boiler top and encompassing a larger preliminary outlet, and an encompassing pool wall spaced outward from said baffle and downward from said boiler top and spaced from said preliminary outlet and said wall extending thence to a point below the liquid level in said boiler thereby embracing a minor part of the disengagement surface therein.

6. A boiler having a dome in combination with a standpipe positioned in said dome containing the vapor outlet, a pool structure surrounding said standpipe below said dome, said structure opening into the boiler at a point below the liquid level therein and also providing a vapor passage at its top, and moisture baffling means interposed between the top of the pool structure and the top of said standpipe.

7. A boiler having a vapor outlet leading from its top, in combination with a vertical baffle encompassing said outlet at a distance therefrom and hanging from the top of the boiler, a still larger open topped pool wall in turn encompassing said baffle and extending downward below the water level in the boiler.

8. A boiler having an opening in its top, in combination with a dome positioned above and closing said opening, a steam pipe leading from the upper part of said dome and an open topped pool wall of greater horizontal area than said opening, and positioned within the boiler below said opening, the top of said wall being spaced from said shell to permit the passage of steam, said pool wall being also open at the bottom and extending downwardly in the boiler to a point below the liquid level therein.

9. A boiler shell having an opening in its top, in combination with a baffle ring conforming to the margin of said opening and extending slightly below the inner side of the shell, a dome positioned above and closing said opening, an outlet positioned in the upper part of said dome and an open topped pool wall of greater horizontal area than said ring and positioned within the boiler below said opening, said pool wall being also open at the bottom and extending to a point below the liquid level therein.

10. A boiler having a vapor outlet leading from its top, in combination with a vertical baffle encompassing said outlet at a distance therefrom and hanging from the top of the boiler, a still larger open topped pool wall in turn encompassing said baffle and extending downward below the water level in the boiler and said wall comprising a plurality

of radially divided sections and hangers therefor.

11. A boiler shell having an opening in its top, in combination with a dome positioned above and closing said opening, a steam pipe leading from the upper part of said dome and an open topped pool wall of greater horizontal area than said opening and positioned within the boiler below said opening, the top 10 of said wall being spaced from the shell to permit the passage of steam and said pool wall being composed of radially divided sections and hangers for separate installation and extending to a point below the liquid level therein.

12. A boiler shell, in combination with a dry pipe leading downwardly from the upper part thereof, a pool structure of many times the cross-sectional area of the dry pipe 20 and comprising a wall surrounding the same, said structure presenting an open bottom below the liquid level in the boiler, and together with the adjacent shell presenting a tortuous vapor entrance passage directly beneath the 25 top of the boiler shell.

13. A locomotive boiler shell having a dome opening in its top, in combination with a dome positioned above said opening, a dry pipe positioned in said dome and extending 30 downward through said opening, an annular wall structure of greater diameter than the said dome opening and suspended and coaxial therewith, said wall structure being suspended and spaced from the top of the 35 boiler and extending downward to a point below the water level of the boiler.

14. A locomotive boiler having a dome opening in the top of its shell, in combination with a dome upon the shell above said opening, a dry pipe leading downward from the interior of said dome and thence forward in the shell, a steam and moisture deflecting flange of substantially the same diameter as said opening and hanging below said shell 40 at said opening, an upstanding wall of larger diameter than said flange and suspended below said flange, and therewith providing at the top of said wall a steam admission opening that is peripherally opposed to said flange, 45 and the chamber within said wall being adapted to receive precipitated moisture.

15. A locomotive boiler having a dome opening in the top of its shell, in combination with a dome upon the shell above said opening, a dry pipe leading downward from the interior of said dome and thence forward in the shell, a moisture deflecting flange hanging from said shell at said opening, an upstanding wall of larger diameter than said 50 flange and suspended below said flange, and therewith providing a restricted steam passage opening adjacent the shell and surrounding the dome opening therein, and said wall extending below the boiler water level.

16. A locomotive boiler having a dome

opening in the top of its shell, in combination with a dome upon the shell above said opening, a dry pipe leading downward from the interior of said dome and thence forward in the shell, a circumferential vertical wall of larger diameter than said opening, suspended below the same and together with said shell 70 providing an annular steam admission passage following the contour of said shell, and said wall extending below the water line in the boiler.

17. A locomotive boiler having a dome opening in the top of its shell, in combination with a dome upon the shell above said opening, a dry pipe leading downward from the interior of said dome and thence forward in the shell, an upstanding cylindrical wall of larger diameter than said opening, suspended from said shell and therewith providing an annular steam admission passage following 80 the contour of said shell, said cylindrical wall defining a chamber opening freely below the boiler water level.

18. A locomotive boiler having a dome opening in the top of its shell, in combination with a dome upon the shell above said opening, a dry pipe leading downward from the interior of said dome and thence forward in the shell, and a steam and moisture deflecting flange hanging from said shell at said opening, an upstanding cylindrical wall of larger diameter than said flange and suspended from 90 said shell, said wall, shell and flange providing a restricted steam admission passage which directs the steam and moisture downward within said wall, said admission opening being of a larger area than said dry pipe, and said cylindrical wall defining a steam and water chamber which opens freely below the boiler water level.

19. The improvement as defined in claim 16 and characterized by said circumferential vertical wall being composed of dismemberable sections of a size permitting introduction and removal through said dome when the latter is open.

In testimony whereof I have hereunto set my hand this 3rd day of March, 1926.

CHARLES GILBERT HAWLEY.
